ELECTRONIC TEACHING MACHINE

Howard Meuche, R. R. 1, Fort Branch, Ind.

Filed Sept. 18, 1962, Ser. No. 71,756

Term of patent 3½ years

(Cl. D25—1)

FIG. 1

FIG. 2

FIG. 3

FIG. 1 is a front perspective view of an electronic teaching machine embodying my design;

FIG. 2 is a top view of said electronic teaching machine; and

FIG. 3 is a side view of said electronic teaching machine.

The rear of said electronic teaching machine is plain and unornamented. The broken line showings of the stored circuit cards are for illustrative purposes only, as is the card plugged into the jack below the meter. The dominant feature of my design resides in the portions shown in full lines.

I claim:

The ornamental design for an electronic teaching machine, substantially as shown and described.
